UNITED STATES PATENT OFFICE.

ERNEST H. METCALF, OF MARLBORO, NEW HAMPSHIRE.

DESIGN FOR AN INHALER.

54,987.

Specification for Design.

Patented Apr. 27, 1920.

Application filed November 3, 1919. Serial No. 335,556. Term of patent 14 years.

To all whom it may concern:

Be it known that I, ERNEST H. METCALF, a citizen of the United States, residing at Marlboro, in the county of Cheshire and State of New Hampshire, have invented a new, original, and ornamental Design for Inhalers, of which the following is a specification, reference being had to the accompanying drawing, forming part thereof.

The figure is a perspective view of an inhaler, showing my new design.

I claim:

The ornamental design for an inhaler, as shown.

ERNEST H. METCALF.
